UNITED STATES PATENT OFFICE.

VICTOR EMMANUEL BENZA, OF BOSTON, MASSACHUSETTS.

DESIGN FOR A MIRROR-FRAME.

SPECIFICATION forming part of Design No. 37,219, dated November 15, 1904.

Application filed June 8, 1904. Serial No. 211,696. Term of patent 7 years.

To all whom it may concern:

Be it known that I, VICTOR EMMANUEL BENZA, a citizen of the United States, residing in Boston, county of Suffolk, Commonwealth of Massachusetts, have invented a new, original, and ornamental Design for a Mirror-Frame, of which the following is a specification, reference being had to the accompanying drawings, forming part thereof.

Figure 1 is a front elevation of a mirror-

frame; and Fig. 2, a side elevation thereof, showing my new design.

What I claim as new, and desire to secure by Letters Patent, is—

The ornamental design for mirror-frame, 15 as shown.

VICTOR EMMANUEL BENZA.
